UNITED STATES PATENT OFFICE

1,983,393

TELEPHONE SET

Herbert F. Obergfell, River Forest, Ill., assignor
to Associated Electric Laboratories, Inc., Chi-
cago, Ill., a corporation of Delaware

Original application July 18, 1932, Serial No.
623,049. Divided and this application May 20,
1933, Serial No. 671,940

2 Claims. (Cl. 179—146)

My invention relates in general to telephone sets and more specifically to the type of set in which the transmitter and receiver are incorporated in a handset unit mounted on the box 5 containing the remaining talking instrumentalities such as calling device, signalling devices, and switchhook operating mechanism.

The telephone set herein disclosed is especially designed for use as a gas-tight telephone for use 10 on air-ships, battle-ships, and the like.

This application is a division of my prior co-pending application Serial No. 623,049, filed July 18, 1932, in which prior application certain features are being claimed.

15 The principal feature being claimed in this divisional application resides in the provision of a spring clip or yielding retaining means for engagement with the handset unit to hold it in position and preventing it from being unintentionally moved or displaced. In this manner it 20 constitutes means for preventing accidental actuation of the hookswitch contacts by movement of the handset.

The above feature is illustrated in the accompanying drawings and pointed out in the following 25 description.

Fig. 1 is a front view on reduced scale of a telephone set embodying my invention.

Fig. 2 is a full-size side view in section showing 30 the switchhook operating mechanism and omitting all except those parts essential to the illustration of the invention herein claimed.

Referring to the drawings, the set comprises a 35 casing 5 of rectangular shape, preferably of aluminum, or light-weight material, upon which are mounted the essential parts for operating the same. An aluminum base plate 6 (Fig. 2) is attached to a suitable supporting surface and supports casing 5 by bolts and nuts 7 and 8. A pair 40 of audible signal horns 10 and 11 are supported on opposite sides of the set by bolts 46. These horns may comprise any desired operating unit such as a receiver having a diaphragm. A visual 45 signalling lamp 12, preferably a neon lamp, is mounted in a socket or base 13 and attached to the top of casing 5 by a pair of bolts and nuts such as 14. A metal guard 15 protects the lamp from damage.

A supporting bracket 20 (Fig. 2) is mounted on 50 the front of casing 5 and has extensions such as 23 for mounting on casing 5 and a handset supporting bracket 25 mounted thereon by bolts such as 21. The bracket 20 also has a pair of oppositely disposed brackets such as 26 which 55 form a support for the switchhook contact and

operating members. The aluminum cover 29 is secured to these brackets by screws 28 and covers the switchhook operating means separately.

The telephone handset member is of well-known construction comprising a handle 30 having a transmitter unit 31 incorporated in one end and in the opposite end a receiver unit 32. This handset unit may be of any preferred construction, the details of which are not pertinent to the invention. A bent spring wire clip 33, shown 60 clearly in Figs. 1 and 2, is secured by means of bolts 34 to the cover 29 and is arranged to resiliently grasp each side of the handle portion 30 of the handset. The purpose of this spring clip 33 is to maintain the handset 30 in a steady upright 65 position and always resting normally on the switch contact-operating member 50 so that the constant swaying or rough motion and movement of the vessel or body upon which the telephone instrument is mounted will not inadvertently 70 actuate the switchhook contacts. This spring member 33, while preventing accidental swaying or unintentional displacement of the handset 30, is not of sufficient grasping strength to prevent 75 the ordinary removal and replacement of the 80 handset when in actual use for talking purposes.

The switchhook-contact-operating mechanism is shown in Fig. 2 and comprises a plunger or push-button member 50 which is normally pressed inward in the casing 29 by means of the 85 handle portion 30 of the handset and when the handset is removed it projects outward. The plunger 50 is journaled in a sleeve which is secured to a supporting bracket 51 which in turn is clamped at each end by means of clamps 52 to 90 the ends of the bracket members 26 and 27 through the medium of screws 53. For a more detailed description and disclosure of a switchhook-operating arrangement similar to that just described, reference may be had to Patent No. 95 1,738,919, issued December 10, 1929, to the same inventor.

The pair of contacts which are utilized to open and close the telephone circuit by the removal and replacement of the handset upon the cradle 100 member 25 are enclosed in a glass tube or vessel 60 which is highly evacuated and entirely sealed, so that the arcing or sparking caused by the opening and closing of the contacts is considerably reduced, thereby preventing burning of 105 the contacts and at the same time also preventing any sparks, which may be generated, from gaining admission to the surrounding atmosphere outside the vessel. The connecting wires are completely sealed in the glass vessel 60 110

and extend out at the right-hand side of the unit. A pair of metal straps 61 spaced apart encircle the glass vessel 60 and securely hold it in position by means of a pair of screws threaded 5 into the side of the bracket 51. In order to actuate the contacts, the glass stem 62 is formed in the vessel and it has one end attached to a corrugated portion formed in the glass and extending to the left-hand end of the tube 60 10 in such a manner that movement of the rod 62 opens and closes the contacts through the medium of the elasticity inherent in the glass. The cam member 57 of the switch-hook-operating mechanism normally bears on one side of the 15 tube 62 and moves it downward, thereby opening the contacts when the handset is in normal position. When, however, the handset is removed from the hook member 25, the pressure of the cam member 57 is removed from the stem 62 20 and the stem assumes its normal position, as shown. This movement is accelerated by means of the leaf spring 63 bearing on the opposite side of the stem 62, which also holds the stem steady. 25 The automatic calling device or impulse sender 70 is mounted below the casing 29 and directly on the front of the box 5 by means of a number of screws 72 threaded to a flange formed around the periphery of the casing 71 containing the 30 mechanism of the calling device. A metal ring 73 is provided on the rear side of the casing 5 to form a means for securely holding the screw 72. The mechanism of the calling device is contained within two separate circular casings 71 35 and 74, preferably made of aluminum. The casing 74 is attached to the rear side of the casing 71 by means of a series of screws 75 around its periphery. The joint between the two casings 71 and 74 is such that it is practically 40 gas- or air-tight. A cover plate 76 attached by means of a series of screws 77 to the casing 74 effectively closes the rear end of the casings containing the mechanism. A circular plate 78 forms a support for the internal operating mech- 45 anism and contact springs of the calling device mechanism, and is attached to the front side of the casing 74 by means of a series of screws 79. A relatively long hollow pin 80 is threaded into one side of the casing 74 and the connecting 50

wires for the contact springs of the calling device are passed through this pin. A suitable amount of plastic insulating compound is forced into the opening provided in pin 80 and around and between the connecting wires so that an air-tight connection is made. It is seen that the casings 71 and 74 are completely air-tight. 80

Reference may be had at this point to Patent No. 1,642,822, granted September 20, 1927, to the same inventor, for an automatic calling device which, except for a certain particular part which will hereinafter be pointed out, is of exactly the same construction as the instant case. All of the parts and mechanisms shown in Fig. 3 of the aforesaid patent are contained within the dotted area of the casing 74, but for the sake of clearness have not been shown therein. 85 90

Although I have described generally certain of the gas-tight features of the set, it will be understood that such features are being claimed in the parent application and that the feature herein relates to the retaining means for the handset illustrated as spring member 33 herein. This device, it will be seen, is useful wherever the set is subjected to jars or motion and effectively 100 prevents false operation of the contacts controlled by the handset. 105

What is claimed is:

1. In a telephone set, a casing, switching mechanism in said casing, a handset unit normally supported at its upper end in a vertical position against said casing and maintaining said switching mechanism in its normal position, and means for yieldingly maintaining said handset unit in its resting position against said casing 110 to prevent accidental actuation of said switching mechanism by swinging of the unit. 115

2. In a telephone set, a casing, a switching mechanism in said casing having an actuating control button projecting from the front of the 115 casing, a handset unit mounted on the front of said casing and normally resting against said button to maintain said switching mechanism actuated, and a spring member engaging said handset unit for yieldingly holding it in position 120 against said button and impeding any swinging action of the unit. 125
